UNITED STATES PATENT OFFICE.

JOHN S. BARNES, OF DETROIT, MICHIGAN, ASSIGNOR OF ONE-THIRD TO LEWIS E. BARNES,
OF DETROIT, MICHIGAN.

LAUNDRY-BUTTON.

No. 869,872.

Specification of Letters Patent.

Patented Nov. 5, 1907.

Application filed September 20, 1906. Serial No. 335,409.

To all whom it may concern:

Be it known that I, JOHN S. BARNES, a citizen of the United States, residing at Detroit, county of Wayne, State of Michigan, have invented a certain new and useful Improvement in Laundry-Buttons, and declare the following to be a full, clear, and exact description of the same, such as will enable others skilled in the art to which it pertains to make and use the same, reference being had to the accompanying drawings, which form 5 a part of this specification.

My invention relates to an improvement in laundry buttons shown in the accompanying drawings and more particularly set forth in the following specification and claims.

15 In the drawings: Figure 1 is a perspective view of the button; Fig. 2 is a similar view of a modification.

The object of my invention is to construct a button of wire which may be manufactured at nominal cost to be used by laundrymen, shirt manufacturers, and 20 others who require a device of this character to hold together the sleeves, wristbands, and collars of shirts and other garments.

25 Referring to the letters of reference shown in the drawings, A is the shank of the button, A' its head, and A² its base.

The head is formed by swaging the end of the wire in the forming machine, and the same operation flattens the base after it is coiled in the form shown. In the variation shown in Fig. 2, the head is formed by twisting 30 the end of the wire in a manner similar to that employed in forming the base of the button. The head in this case is also flattened that it may more readily enter the button-hole of the garment.

The machine employed to construct this button is the subject-matter of another application.

35

Having thus described my invention, what I claim is:—

1. A button formed of a single piece of wire, one end of the wire being bent to provide a circular base with a smooth periphery and the opposite end formed into a circular head with a smooth periphery and concentric with the base, the intermediate portion of the wire forming a straight shank arranged centrally of the head and base. 40

2. A button formed of wire, one end of the wire being bent to provide a circular base with a smooth periphery and a circular opening, and the other end being formed into a circular head with a smooth periphery and of smaller diameter than the base, a portion of the wire between the head and base lying within the opening of the base and another intermediate portion of the wire being arranged centrally of the base and head to form the shank of the button, the base end of the wire being flattened. 45

3. A button formed of a single piece of wire, one end of the wire being bent to provide a circular base with a smooth periphery and the opposite end formed into a circular head with a smooth periphery and concentric with the base, the intermediate portion of the wire forming a straight shank arranged centrally of the head and base, the base end of the wire being flattened. 50

4. A button formed of a single piece of wire, one end of the wire being formed into a head and the other end being formed into a base having a central opening, one part of the intermediate portion of the wire being directed into said opening with another part of the intermediate portion directed at an angle to the first part forming a straight shank for the button. 65

In testimony whereof, I sign this specification in the presence of two witnesses.

JOHN S. BARNES.
